UNITED STATES PATENT OFFICE.

JAMES H. BULLARD, OF SPRINGFIELD, MASSACHUSETTS.

SPEEDOMETER.

No. 816,639.

Specification of Letters Patent.

Patented April 3, 1906.

Application filed December 30, 1904. Serial No. 239,001.

To all whom it may concern:

Be it known that I, JAMES H. BULLARD, a citizen of the United States of America, residing at Springfield, in the county of Hampden and State of Massachusetts, have invented new and useful Improvements in Speedometers, of which the following is a specification.

This invention relates to recording instruments, and has special reference to instruments of this class in which the record-disk is operated by a time-movement, marks being imprinted or impressed on the record-disk from a source outside of the time-movement to indicate a number of periods recurring within a given time.

The object of the present invention is particularly to provide a recording instrument associated with a time-movement, as an ordinary clock, the record-disk and the clock-dial occupying the same face of the instrument, whereby they may be read simultaneously.

The invention further comprises means to operate the record-dial from the minute-hand of the time-movement, said dial being removable therefrom independently of the hour-indicating dial.

The invention consists, further, in suitable mechanism for rotating the hour-dial by a single movement at the end of each hourly period by means of mechanism controlled by but not operated from the time-movement.

Still another object of the invention is to provide means to print or impress on the record-dial hourly records, each occupying a line extending entirely around the dial, the lines of the record being concentrically disposed instead of spirally disposed.

Having these various objects in view, the invention consists in the construction set forth in the following specification, and clearly pointed out in the claims appended thereto.

The invention is clearly illustrated in the drawings accompanying the specification, in which—

Figure 1 shows a sectional elevation of the device, the plane of the section being on line 11, Fig. 2. Fig. 2 is a sectional elevation in a plane at right angles to Fig. 1, the plane of the section being on line 22 of the last-named figure. Fig. 3 is a front elevation of the instrument with the record and record-dial and hour-dial in operative position thereon. Fig.

4 is a perspective view of a portion of the hour-dial, showing its means of support, dotted lines showing the position to which the dial may be moved. Fig. 5 is a front elevation of a cam mounted on the hour-arbor, a portion of the lever being shown whereby the hour-dial is rotated and whereby the puncturing or printing recording device is shifted radially of the dial. Fig. 6 is a side elevation of the parts shown in Fig. 5 and shows the manner of supporting the lever which rotates the hour-dial, whereby movement may be imparted to said lever lengthwise of the axis thereof to effect its temporary disengagement from its operating-cam. Fig. 7 is a diagrammatic view of a circuit-breaking mechanism whereby movements may be imparted to any suitable printing or puncturing device associated with the recording instrument by means of an electromagnet. Fig. 8 shows a detailed construction of a solenoid to operate the puncturing or printing mechanism. Fig. 9 is a rear elevation of the electromagnet-support and the electrical connections therewith.

This instrument is designed particularly to record the speed of vehicles, the record being imprinted or impressed on a dial rotated by and in consonance with the minute-arbor of a clock-movement, the disk being divided by radial lines, as shown in Fig. 3, to indicate minutes, the record of speed for each hour being displayed in concentric circles and the record being constantly visible to the operator of the vehicle.

Assuming that the device is employed to record the speed of an automobile, the circular casing *a*, Fig. 2, would be secured to the vehicle in some position where the disk on the front of the instrument would be easily visible. This circular casing is arranged to receive a cylindrical case *b*, which contains the clock-movement, with which the recording-disk is associated, and also the puncturing device or the printing device, whereby the record of the distance traveled may be imprinted or impressed on the disk in such manner as to make the latter legible on the face thereof. The particular mechanism whereby the casing of the puncturing device is operated is of minor importance—that is to say, the kind or type of mechanism used to actuate the printing or puncturing stylus is unimportant and is not an important part of the present invention and will be claimed only

herein as a device suitable to actuate said stylus. An electrically-operated device to operate the stylus is shown in the drawings, as a device of this character is very easily applied and adapts itself readily to the end in view; but it is not essential that it should be electrically operated.

The cylindrical clock-case *b* is provided with a glass front *c*, supported in position on the case by the usual face-ring *d*. Inside the clock-case the usual time-movement is provided mounted in the rectangular frame *e*, the latter being shown in Figs. 1 and 2 particularly. Only a portion of the time-movement has been shown in these drawings—that is to say, the central arbor, which is the only one with which any connection is made—all of the other devices associated with the instrument being so applied to the clock-movement as to not interfere with the ordinary construction of the latter. The hands of the clock are eliminated. The central arbor consists, as usual, of a shaft and a sleeve thereon, the sleeve rotating once in twelve hours and the shaft once an hour. The shaft is indicated by *f*, and the sleeve by *f'*. The central shaft of the clock mechanism is extended far enough beyond the face of the record-disk *g* to permit the application thereto of a disk *h*, bearing around the edge thereof numerals running from "5" to "60," dividing said disk into twelve spaces. Outside of said disk is a circular plate *j*, and screwed onto the end of the shaft *f* is a thumb-nut *k*. Fixed on the arbor back of the disk *g* is another disk *m*, which serves as a support between which and the circular plate *j* the disk *h* and the disk *g* are clamped. On the disk *m* is a pin *o*, which extends beyond the face of the disk far enough to receive the disk *g*, the disk *h*, and the plate *j*, which are each provided with a hole for the pin *o*, whereby these parts may always be applied in the same position relative to the disk *m*, whereby when the record-disk is applied the numerals on the disk *h* will be in proper relation to the exposed figure on the hour-dial *p*. When the numeral "60" is in the position of 5 in Fig. 1, it will indicate the point on the record-disk at which the hourly record begins, and it is when this number "60" arrives in this position that the radial shifting of the puncturing or printing stylus *q*, Fig. 2, is effected to begin said hourly record in one of the circular paths comprised between the concentric lines *r*, Fig. 3. A glance at said disk *g* in this last-named figure will thus clearly show that these annular spaces comprised between the lines *r* will contain the record for each hour, that the space between the radial lines *s* will contain that portion of the hourly record made in each five minutes, and that portion of the disk *g* comprised between the lines *t* will contain the record for each minute of the hour. To tell the time by means of the hour-

dial and the record-disk, it is only necessary to glance at the figure of the hour-dial *p* which is exposed through the opening *u* at the top of the instrument and to glance at the figure on the disk *h* directly under the figure on the hour-dial. The latter changes instantaneously at the end of each hour, as will be described farther on.

A sort of hollow plug *w* is inserted through the case *b* at right angles to the axis of the latter and at the lower edge thereof just behind the glass face *c*, the base of the plug having a flange *w'*, whereby it may be secured to the case by screws, and in said plug is mounted on a stem *x* a cylindrical pad *y* of some material which will absorb colored ink, one side of said cylinder lying in close proximity to the front of the record-disk *g*, the latter being made, preferably, of relatively stiff paper. This stem *x* extends through the casting and is provided with a thumb-nut *x'*, whereby it may be rotated. Lying directly back of the plug *w* is an electromagnet 3, preferably in the form of a solenoid, a detail of which is shown in Fig. 8. Reference to this figure shows that the armature 4 of the solenoid 3 is connected by a cross-head 5 at the rear end thereof to posts 6, extending from the ends of said cross-head to a plate 7, extending across the front of the solenoid, constituting a sort of frame, actuated by the solenoid to move toward the back side of the record-disk *g*. The plate 7 is provided with a vertical groove 8, which is T-shaped in cross-section, in which the puncturing or printing stylus *q* may slide freely. Said plate and posts 6 are supported at one end by the solenoid and at the opposite ends thereof by the plates 6^a, through which the posts 6 pass, said plates being secured to or forming part of the frame *e*. A lever 9, pivotally supported on the clock-frame at 10, is provided with a forked end to engage said stylus, the opposite end of the lever also being forked to engage a pin 12 in the end of an elbow-lever 13, pivotally supported on the frame of the clock at 14, the upper arm of said lever being provided with a segmental rack 15, which engages a pinion 16, fixed on the shaft 17 of the hour-dial *p*. The lower end of the segmental rack, as shown in Fig. 4, is provided with an inturned end 18, which bears normally on the outer edge of a step-cam 19, which is shown in Figs. 2, 5, and 6 of the drawings. This cam 19 is a spiral cam and is secured on the sleeve *f'*, and consequently rotates with the latter once in twelve hours, and is provided with steps 20 on the periphery thereof the distance between each of which is equivalent to one hour. The shaft 14, which constitutes the axis of the elbow-lever 13, extends across the frame of the clock, as shown in Figs. 2 and 6, and is provided with a spring 21, which has the double function of pressing the elbow-lever toward the cam 19, and it is also a tor-

sional spring, whereby the inturned end 18 of the segmental rack is yieldingly pressed against the edge of the cam and toward the axis of the latter. Therefore as the cam is 5 rotated by the movement of the clock mechanism whenever the hour has been completed the inturned end 18 of said elbow-lever runs off one of the steps 20 of the cam, and the pinion 16 is thereby rotated, carrying 10 the hour-dial *p* one-twelfth of a revolution. When the cam has rotated such a distance as to cause the end of the elbow-lever 13 to drop off the last step, the inturned end 18 of said lever will drop onto the sleeve *f'*, 15 as shown in Fig. 5, on which it may rotate indefinitely without imparting further movement to the hour-dial *p*. To permit this movement of the end of the elbow-lever 13, the hub of the cam has an annular channel or 20 groove 22 cut therein, as shown in Fig. 5, the wall of which is cut away at the foot of the last of the steps 20 to permit the rectangularly-disposed end 18 of the elbow-lever to enter said groove, the point at which this hub 25 is cut away being indicated at 23, Fig. 5. It is evident, therefore, when it becomes necessary to put on a new dial this inturned end 18 of the elbow-lever 13 must be disengaged from said groove 22, and this is effected by 30 opening the front of the instrument and pressing on the shaft 14, on which the elbow-lever is secured, moving the latter toward the back of the casing far enough to disengage the end 18 and then rotating the shaft 14 to 35 swing the upper arm of said lever upward to the position shown in Fig. 1, which will rotate the hour-dial *p* back to twelve o'clock, provided the cam is in the position it would occupy at twelve o'clock. Otherwise the lever 40 will swing down onto the edge of the cam and set the dial *p* to the correct hour, for the cam being continuously rotatable will be in position to set the hour-dial at whatever point the lever 3 will be located on the cam in resetting. 45 The cam being frictionally secured on its arbor may be adjusted, whatever may be the hour at which the record begins, so that the end of the lever 13 will rest on the highest point of the cam, thus insuring a full twelve-hour record. When this change of 50 adjustment of the cam is effected, it becomes necessary to change the relation of the hour-dial to its actuating-rack 15, and for this purpose this dial may be moved to disengage its pinion 16 from the rack 15, and to this end 55 its shaft 17 is endwise slidable in its bearings 23, and, as shown in the drawings, the shaft 17 is supported therein by one end only, and there is an annular groove between the dial 60 *p* and the end of the pinion 16 into which an arm 24 may drop, said arm, if desired, being held in engaging position by a spring 25. In 65 said Fig. 4 a portion of the arm 24 is shown in a raised position in dotted lines. It is thus apparent that the adjustment of the dial *p*

may be made independent entirely of the rack 15. Obviously a record-disk may be put on at any time before the cam 19 has completed its cycle, and the record will begin in that one of the concentric spaces, counting from the outermost inward, which corresponds with the number of steps 20 on the cam which have passed under the end of the lever 13. 70

Referring now to Figs. 2 and 9, it is seen 75 that the solenoid 3 is supported on a piece of insulating material 26, which by a screw 27 is secured to the back side of the clock-frame *e*, and to this piece 26 two spring-fingers 28 and 29 are secured with which the ends of the 80 wire 30 are connected, with which the solenoid is wound.

Secured to the casing *a* and insulated therefrom are two spring-fingers 31 and 32, which are connected with binding-posts 33 on the 85 back side of the case *a*, from which posts the wires 34 extend which constitute the electrical circuit shown in Fig. 7, and in which figure the solenoid is conventionally shown only and the circuit comprising a battery or 90 other suitable source of electricity 35. One terminal of the circuit is secured to a stationary spring-finger 36, located in suitable position to bear on a rotating member 37, which ordinarily is rotated by the hub of the wheel 95 of the vehicle, and on this member are metal ribs 38, which are electrically connected with the other terminal of the circuit, whereby as the member 37 rotates and these strips come in contact with the finger 36 the circuit will 100 be closed and the solenoid 3 energized, thereby causing the plate 7, connected with the armature of the solenoid and bearing the stylus *q*, to be moved sharply toward the back side of the record-disk *g*, bringing the stylus 105 into contact with the latter and forcing it against the inked pad *y*, causing a spot or point to be printed on the front of the dial. As soon as the circuit is opened by the rotation of the member 37 the spring 39, (see Fig. 110 8,) located between the end of the solenoid-coil and the cross-head 5, will retract the plate 7 and the stylus. This movement takes place so quickly as not to interfere in any way with the rotation of the record-dial. 115 Referring again to Fig. 7 and assuming that the rotating member 27 is moved at such speed that the circuit will be closed to indicate each quarter-of-a-mile run, then at some point on said rotating member the metal ribs 120 38 will be doubled, as shown, whereby a double dot would be printed on the record-dial at the end of each mile. The hour which appears in the aperture *u* of the case will indicate the hour at which the rotation of the 125 cam was completed, and consequently when the record was finished. Therefore by taking note of this when a new record-disk is put on some time after note may be made on the completed record of the time at which 130

the run finished, the hour being indicated as above and the minute by observing at what point on the dial relative to the figures surrounding the inner edge thereof the record terminates.

It is of course quite obvious that the dial *p*, indicating the hour, may be dispensed with altogether; but this would not affect in any way the operation of the device as a speed-
cording instrume¹⁰.

It is to be noted that each of the annular spaces comprised between the lines *r*, Fig. 3, on the record-disk is the space allotted to each hourly record, the disk rotating once in that time. Therefore the cam 19 is so laid out that the number of steps in its periphery will coincide with the number of these annular spaces referred to. Furthermore, it is to be noted that when the inturned end 18 of the arm 13 falls off the last step and into the annular groove 22 the largest diameter of the cam lies directly over the end of the last step of the cam, and therefore as soon as one record-disk has been filled another may be put on to take its place immediately, if desired, and the arm 13 pushed back and swung up over the edge of the cam again. If the record-disk is not replaced, it will continue to run without, however, receiving any record within the spaces between the lines *r*. The stylus, however, will continue to mark the disk, but always in the same path on the margin thereof outside of the record-spaces, and the dial *p* will remain stationary at the point where the last record was completed, the numerals on this dial, together with the point of termination of the record, constituting a record of the time at which the run was completed. It is therefore seen that some means to reset the time-dial *p* is necessary, as any length of time may elapse between the completion of one record-disk and the beginning of another, and this adjustment of the time-dial has been above explained.

From the foregoing description it is clear that this instrument combines a clock to show the lapse of time and a record-dial to indicate and record the speed of the vehicle for each minute of the time elapsed, both the clock-face and the dial-face being on the same side of the instrument and easily readable together, the record-dial being easily removable by simply opening the face of the instrument.

Obviously the inked pad may be dispensed with and a puncture serve to mark the dial.

Having thus described my invention, what I claim, and desire to secure by Letters Patent of the United States, is—

1. In an instrument of the class described, the combination with a suitable power mechanism, of a record-disk rotating continuously at minute-hand speed and receiving during its rotation the record of successive occurrences, and a time-dial having a partial rotary move-

ment at periods, said time-dial being arranged in complementary relation to the record-disk on the same side or face of the instrument.

2. In an instrument of the class described, the combination of a power mechanism having an arbor rotating at minute-hand speed, a record-disk turning with said arbor and having minute-period indications, a separate time-dial having hour-period indications and exposed for reading on the same side or face of the instrument as the record-disk, and means for periodically rotating the time-dial to bring its indications into complementary reading relation to those of the record-disk. 75

3. In an instrument of the class described, the combination with a clock mechanism and the center arbor thereof, of a record-disk supported on, and rotatable with the latter, a device to mark the dial intermittently during its rotation, a second time-disk and suitable mechanism to impart partial rotatory movement to the time-disk synchronously with the radial movement of the marking device. 80

4. In an instrument of the class described, the combination with a clock mechanism and the center arbor thereof, of a record-disk supported on said arbor to rotate at minute-hand speed, a helical cam supported on said arbor to rotate at hour-hand speed, said cam having steps on its periphery corresponding to hourly divisions of time; a second time-disk; a device to intermittently mark the record-disk during its rotation, and a member bearing on the periphery of the cam and connected with the marking device and with the time-disk, whereby the passing of a step of the cam will shift the marking device radially of the record-disk, and impart partial rotatory movement to the time-disk. 90

5. In an instrument of the class described, the combination with a clock mechanism and the center arbor thereof, of a record-disk supported on said arbor to rotate at minute-hand speed, and provided with radial divisional lines to indicate minute periods; a second time-dial provided with hour-divisions indicated by numerals; said time-dial being rotatably supported on a separate arbor; and exposed for reading at the same side or face of the instrument as the record-disk and bearing a complementary relation to the latter mechanism to mark the record-dial during its rotation, and means of connection between the marking mechanism and said time-dial, whereby it may be rotated at periods to shift from one hour to the next for each revolution of the record-disk. 110

6. In an instrument of the class described, the combination with a clock mechanism and the center arbor thereof, of a record-disk supported on said arbor to rotate at minute-hand speed, and provided with radial divisional lines to indicate minute periods; said periods being indicated by numerals; a sec- 125

ond time-dial provided with hourly divisions indicated by numerals, both dials being readable on the face of the instrument, mechanism to rotate said record-disk continuously, 5 and means to rotate the time-dial to bring each hourly division thereof into a certain position relative to a fixed point at the completion of each revolution of the record-disk.

7. The combination of a clock mechanism 10 and a center arbor thereof, of a record-disk supported on the arbor to rotate at minute-hand speed, a helical cam supported on said arbor to rotate at hour-hand speed, a marking device for the record-disk, a lever bearing 15 on the periphery of the cam and connected with the marking device to move the latter radially of the disk by the movement of one end of said lever toward the axis of the cam, the latter having an annular groove in the 20 hub thereof opening toward the side of the cam, there being an opening extending into said groove at right angles to the axis of the cam to permit the end of the lever bearing on the cam to drop into said groove; said lever 25 being movable away from the cam to disengage it from the groove in the latter and to

permit its engagement again with the periphery of the cam.

8. In an instrument of the class described, 30 the combination of a clock mechanism and the usual rotatable center arbor therefor, of a record-disk supported on the arbor, a device to mark the record-disk, and electrically-actuated means to actuate the marking device comprising an electromagnet within the instrument and a circuit extending through the casing of the instrument and including said magnet, a battery and a make-and-break device, together with other means to automatically break the circuit when the instrument 35 is removed from its support.

9. In an instrument of the class described, 40 a rotatable record-disk and mechanism to mark a record on said disk in paths encircling the axis thereof, certain points in the path 45 of the recording-marks being distinguished from the others by a change in the character of the mark.
